[57] **CLAIM**

The ornamental design for a large loft angle golf club head, as shown and described.

DESCRIPTION

FIG. 1 is an elevational view looking at the toe end of a large loft angle golf club head showing my new design;

FIG. 2 is a rear elevational view thereof;

FIG. 3 is an elevational view looking at the heel end thereof;

FIG. 4 is a view of the top edge of the face of the large loft angle golf club head of my design looking from the position indicated by the line 4—4 of FIG. 1;

FIG. 5 is a top view thereof;

FIG. 6 is a front elevation thereof;

FIG. 7 is a view of the sole of the large loft angle golf club head of my design looking from the position indicated by the line 7—7 of FIG. 1; and,

FIG. 8 is a bottom view thereof.

The characteristic feature of my design resides in the sole of the club head having a first longitudinally extending surface in juxtaposed relationship with the lower edge of the face of the club head with this first surface disposed to form an acute angle with the face of the club head and a second surface which is coextensive with the first surface and forms an obtuse angle with the first surface.
